prop 27 and the bracket or ledge 15 all lying in substantially the same plane. In its operative position the frames 1 and 2 are maintained in any desired open position by means of the prop 5 27 and its extension 28. The ledge 15 is swung to its open position at right angles with the turntable, the backbone of the book to be supported on the turntable is slipped beneath the finger 25 until its lower edge rests on the ledge 10 15, and then the spring fingers 19 and 21 are disengaged from their sockets 23, and rotated to a position wherein the beads or balls engage the margins of the leaves of the book. In this position the frame 2 and consequently any book 15 supported thereby may be rotated as desired about an axis generally defined by the fitting 3 and the setscrew 31, and the book may be rotated on its turn table to any desired angle. Preferably the diameter of the lower frame 1 should be such as to permit the frame 1 to be passed over 20 the knees of a reader, for it has been found that when an individual is in a partially reclining position with his knees up the book rest as above described may be used with considerable advantage. In passing it is to be noted that the infinite 25 number of adjustments to which a book rest of this character is susceptible, provides a means

by which reading matter may be held in proper position relative to a reader's eyes, regardless of whether the reader has assumed a semi-reclining position on his back, or whether he has turned on one side or the other. 5

I claim:

1. A book rest comprising: a lower frame; an upper annular frame hinged to the lower frame; a channel formed in the inner periphery of the upper frame; a table rotatably disposed in said channel and a prop associated with said frames for holding their free ends in spaced relation. 10

2. A book rest comprising: a lower annular frame; an upper annular frame secured to the lower frame by means of a universal connection 15 and concentric therewith when the frames are in a collapsed position; a channel formed in the inner periphery of the upper frame; a turn table supported within said channel; a ledge hinged to said turn table; and a prop secured at one end 20 to the free side of the lower frame and at its other end to the free side of the upper frame.

3. A book rest comprising: a lower frame having a central opening therein adapted to accommodate the knees of an individual; and an upper 25 frame hinged to said lower frame.

URSULA SAWYER.
